UNITED STATES PATENT OFFICE

THOMAS E. McNULTY, OF ALAMEDA, CALIFORNIA

CURTAIN GUIDE

Application filed September 16, 1929. Serial No. 392,998.

The invention forming the subject matter of this application relates to guiding devices for shades or curtains.

The primary object of the invention is the provision of a device for suspending a window shade in such a manner as to prevent the flapping of the ends and the edges thereof, at the same time allowing a variety of adjustments of the window shade positions, means being provided to positively guide the window shade or curtain in its movement while the same is brought from one position into another desired position.

Another object of the invention is the provision of a guiding device for a window shade or curtain, which is suspended in operative relation to a window, said guiding device positively maintaining the window shade in true alignment at all times and preventing the binding of the window shade on its guides.

Another object of the invention is the provision of parallel guides for a window shade, which shade or curtain is suspended on a pull cord in such manner as to hold the free end of the window shade stationary and allow the movement of the spring roller of said shade relatively to the free end thereof; means being provided on the opposite edges of said window shade or curtain for positively guiding the window shade in its movement on the guides; furthermore, the window shade is provided with a positioning element adjacent the spring roller thereof for the purpose of arresting the rolling and unrolling of the shade. The entire window shade may be raised and lowered as a unit, and the free end of the shade may be made stationary whereby the window shade may be rolled and unrolled to any desired extent.

Other objects and advantages are to provide a guiding device for shades or curtains, that will be superior in point of simplicity, inexpensiveness of construction, positiveness of operation, and facility and convenience in use and general efficiency.

In this specification and the annexed drawing, the invention is illustrated in the form considered to be the best, but it is to be under-

stood that the invention is not limited to such form, because it may be embodied in other forms; and it is also to be understood that in and by the claims following the description, it is desired to cover the invention in what-soever form it may be embodied. 55

The invention is clearly illustrated in the accompanying drawing in which

Fig. 1 is a front view of my window shade guiding device, supporting a window shade 60 on a window;

Fig. 2 is a side elevation of the device shown in Fig. 1;

Fig. 3 is a fragmentary detail front view of the spring roller locking mechanism of the 65 window shade and of its connection to the guide;

Fig. 4 is an end view showing the attachment of the shade spring roller relatively to the guide; 70

Fig. 5 is a fragmentary detail plan view of an end of the spring roller;

Fig. 6 is a detail view of the pull cord locking pulley;

Fig. 7 is a sectional detail view of the pull 75 cord pulley, the section being taken on the line 7—7 of Fig.; and

Fig. 8 is a detail view of the guide holding element of my device.

In its general organization my device comprises a window shade 6, suspended on a pull cord 7, and slidably guided on parallel guides 8, which guides 8 are mounted on the window 9. 80

The window shade 6 is of the roller shade 85 type, and one end thereof is wound around a spring roller 11, while the other end thereof is provided with a strip 12 to the center of which is attached an end of the pull cord 7. It will be noted that the spring roller is not 90 mounted fixedly on the window, but it is movable relative thereto. In order to arrest the movement of the roller 11 relatively to the strip 12, I provide a positioning bar 13 so disposed as to bear against the under side of 95 the window shade. On each end of the bar 13 is secured a socket 14 having a central opening 16 therein, in which opening is rotatably supported a retainer loop 17; the latter is formed of a bent wire, the ends of the wire are 100

re bent outwardly so as to engage the inner surface of the socket 14, adjacent the opening 16.

These retainer loops 17 are slideable on the 5 respective guides 8. The bar 13 is rotatable around its axis without disturbing the proper connection of the ends thereof with the guides 8. The turning of the bar 13 is accomplished by the use of a handle 18 thereon.

10 The spring roller 11 is of the usual construction; the ends of its shaft are fixedly held relatively to the positioning bar 13 by means of brackets 19, which brackets are fixedly attached to the bar 13. The window 15 shade or curtain 6 is so wound on the roller 11 that its under side bears against the bar 13 as clearly shown in Fig. 4, therefore when the positioning bar 13 is freely suspended, then the weight of the spring roller 11 holds 20 the roller 11 below the bar 13, thereby holding the shade 6 in frictional engagement with said bar 13, thus preventing the unrolling of the shade. In order to unroll the shade, it is necessary to turn the handle 18 and the 25 bar 13 therewith, outwardly, away from the window casing, so that the shade 6 is freed from the frictional engagement with the bar 13; and then pull the bar 13 downwardly, away from the strip 12, thus unrolling the 30 released shade 6 to any desired extent. The releasing of the handle 18 and the return of the roller 11 to its original position by its own weight, automatically arrests any further unrolling or rolling of the shade 6. The 35 raising of the shade is effected similarly to the lowering, by moving the rolled end of the shade toward the strip 12, the spring roller acting in the usual manner.

40 The guides 7 are preferably made of suitable wire stretched between brackets 21 and secured thereto by screws 22. Each bracket has a horizontal protrusion 23 thereon in which is a slot 24. The wire guides 7 are disposed in the respective slots 24, and are 45 thus prevented from lateral movement and are spaced from the window 9. There is one guide 7 on each side of the shade 6, the guides being parallel with each other. The bar 13 is adjustable on the guides when the 50 shade is raised or lowered, and is maintained in true relative position by its swivel, retaining loops 17 which surround the respective guides 7. The shade is raised or lowered in 55 its entirety without binding or without accidental rolling or unrolling the shade. This is made possible by the arresting of the spring roller action in any desired position. Thus by lowering or raising the strip 12 by means of the cord 7, the entire shade is adjusted to any position on the window, as a 60 unit.

In order to further obviate binding of the shade movement on the guides and particularly to lend proper guiding to the ends of 65 the strip 12, I secure a clevis 26 on each end

of said strip. The U-shaped end of each clevis 26 extends beyond the end of the strip 12, and is so perforated as to receive the guide wire 7 therein. In this manner my window shade is provided with three points of sliding support at each edge thereof, namely the loop 17 and two perforations of the U-shaped end of the respective clevis 26. The use of the clevis 26 on each end of the strip maintains the entire shade in true position relatively to the guides 7 and to the window. The proper alignment of the shade with the guides, obviates binding on the guides, and greatly facilitates the lowering or raising of the entire window shade in both rolled and unrolled position.

As heretofore stated, the entire shade is suspended on the cord 7, which in turn is guided on a pulley 27. The pulley 27 is rotatably supported in a bracket 28 fixed on the window casing. The pulley 27 is of the locking type, it is provided with the usual threads at the opposite ends thereof, so that when the cord 7 is pulled over said threads it is locked therein, also locking the pulley 29 against rotation, whereby the entire shade is suspended in its adjusted position. When the cord 7 is thus fixed, it prevents the downward movement of the strip 12, therefore the 95 rolling and unrolling of the shade to any desired degree is effected by the moving of the spring roller 11 toward or away from the strip 12 in the manner heretofore set forth.

It will be recognized that the aforedescribed guides and supports for a rolling 100 shade positively maintain the shade in any adjusted position, and allow a great variety of adjustments of the shade position. The device is simple and rugged in construction and positive in operation; it does not require 105 any careful setting up or adjustment, therefore it readily lends itself to effective application and use.

Having thus described this invention, what I claim and desire to secure by Letters 110 Patent is:

1. A shade apparatus adapted to be used on a window frame comprising a window shade, adjustable means on the window frame engaging the free end of the shade to suspend the same and being adapted to move the entire shade as a unit into selected positions on the window, means on the other end of the shade upon which the shade is rolled, releasable means operatively related to said 115 shade rolling means to normally arrest the operation of the latter and prevent the rolling and unrolling of the shade, guiding elements on the window frame, one adjacent each longitudinal edge of the shade, and means of connection between the shade arresting means and the guide elements to adjustably hold the former on the latter.

2. In a shade apparatus adapted to be used on a window, a window shade, adjust-

able means supported on the window for suspending the shade by its upper end; a spring roller on the lower end of the shade on which the shade is rolled; guides on the 5 window adjacent the longitudinal edges of the shade; a positioning element slidably connected to said guides; and means to rockably suspend the roller on said element, the shade being passed between the positioning 10 element and the roller, the weight of the roller normally holding the shade in frictional engagement with the said element, said roller being movable away from the plane of the window to release the shade from 15 said frictional engagement.

3. In a shade apparatus for use on a window frame, a window shade, adjustable means on the window frame connected to the upper end of the shade to suspend the shade; 20 a spring roller on the lower end of the shade for rolling the shade when the roller is moved toward said upper end; guides on the window frame adjacent the longitudinal edges of the shade; and a positioning element slidably and rockably connected to the guides, the spring roller being connected to the positioning element to move with the positioning element as the latter is rocked, the unrolled portion of the shade extending between the 25 roller and the positioning element and being normally held in frictional contact with the positioning element by the weight of the roller.

4. In a shade apparatus for use on a window frame, a window shade; adjustable means supported on the window and connected to the upper end of the shade to suspend the shade; a spring roller on the lower end of the shade for rolling the shade when the 30 roller is moved toward the upper end of the shade; guides on the window adjacent the edges of the shade; a positioning element; means to slidably and rotatably connect the positioning element to the guide; and means 35 to connect the spring roller to the positioning element to move the roller toward and away from the window as the positioning element is rocked, the shade being extended between the roller and the positioning element and being 40 normally held in frictional engagement with the positioning element by the weight of the roller to arrest the unrolling of the shade.

5. In a shade apparatus for a window, a window shade, adjustable means supported 45 on the window for suspending the shade by its upper end; a spring roller on the lower end of the shade for rolling the shade; guides on the window adjacent the edges of the shade; a positioning element, said spring roller being mounted on said positioning element and being spaced therefrom, the shade being passed between the positioning element and the roller; connections at each end of the positioning element to slidably and rotatably 50 connect the same to the respective guides

forming a rockable suspension for the roller, the roller being normally held below the positioning element holding the shade in engagement with the positioning element to arrest the unrolling of the shade, the roller being 70 rockable around said connections to release the shade from the positioning element.

6. In a shade apparatus for a window, a window shade adjustably suspended by its free end; parallel guides on the window adjacent the edges of the shade; a spring roller on the shade movable toward said free end to roll said shade; a positioning bar in parallel, fixed connection with the spring roller; adjustable means to slidably connect the bar 75 to the guides, the shade being passed between the bar and roller, said connecting means being adapted to suspend the bar and the roller in a position to hold the shade in engagement with the bar to arrest the unrolling of the shade, and being adjustable to turn the roller around the bar to release the shade.

7. In a shade apparatus for use on a window, a window shade adjustably suspended by its free end on a window; parallel wire 80 guides at each edge of the shade; means extending from the edges of the shade at the free end thereof to slidably engage said guides; a spring roller movable relatively 85 to the said free end so as to roll and unroll said shade; a positioning element on which the spring roller is fixedly mounted; guiding the shade; a positioning element slidably 90 engage the guides; means to suspend the roller below said element the shade being passed 95 between the roller and said element and being held in engagement with the said element by the weight of the roller, said positioning element being rotatable around said guiding means to release the weight of the roller from 100 the engaged portion of the shade.

8. In a shade apparatus for use on a window frame, a window shade adjustably suspended by its free end on a window; parallel wire guides one at each edge of the shade; U-shaped members extending from the opposite edges at the free end of the shade and having perforated ends to provide a double 105 slidable engagement with the guide thereat; a spring roller movable relatively to the said free end upon which roller the shade is rolled; a positioning bar secured to, and parallel with, the spring roller, said shade being passed between said bar and roller; means at each end of the positioning bar to 110 guide said bar on the guide wires, the bar being rotatable on the said means, the shade being normally held in engagement with the bar by the weight of the roller to prevent the unrolling of the shade, said bar and roller being adjustable to release said shade from 115 said engagement.

9. In a shade apparatus for use on a window frame, a window shade adjustably suspended by its free end on a window; parallel 120

wire guides one alongside each edge of the shade; U-shaped members extending from the opposite edges at the free end of the shade and having perforated ends to provide a double slidable engagement with the guide thereat; a spring roller movable relatively to the said free end on which the other end of the shade is rolled; a positioning bar secured to, and parallel with, the spring roller, said shade being passed between said bar and roller; and a guide loop being rotatably mounted in each end of the bar for sliding engagement with the adjacent guide wire, the weight of said roller urging the underside of the shade against the bar when the roller is in freely suspended position.

10. In a shade apparatus adapted to be used on a window, a shade, adjustable means on the window to hold the shade suspended by the free end thereof, a spring roller on the other end of the shade, a guide on the window alongside each edge of the shade, means of connection between the free end of the shade and said guides to slidably align the shade 20 relatively to the window, an element on one side of the shade being slidable on the guides and rotatable around its axis, means on the element to support the spring roller, said shade being passed between said element and the spring roller while being rolled and unrolled, and being releasably held in engagement with said element at other times to prevent the rolling and unrolling of the shade.

11. In a shade apparatus adapted to be used on a window, a window shade having its upper end free, a spring roller on the lower end of the shade upon which the shade is rollable, an adjustable member supported on the window and engaging the free end of the shade to hold the same suspended on the window; a pair of guides on the window, one alongside each edge of the shade; a positioning bar disposed between the window and the shade, said bar being slidably connected to said guides and being rotatable, means to connect the roller to said bar so that said roller is swingable toward and away from the window as the bar is rotated normally to urge the shade into engagement with the bar, and to release said engagement when the roller is swung away from the window thereby allowing the unrolling of the shade.

12. A shade apparatus adapted to be used on a window frame comprising a window shade, adjustable means engaging an end of the shade to suspend the entire shade, a shade roller on the shade, means to render said shade roller turnable at one time and to keep it from turning other times as the shade is moved, guide elements on the window frame adjacent the longitudinal edges of the shade, and means on the free end of the shade to slidably connect the shade to the respective guide elements.

13. A shade apparatus adapted to be used

on a window frame comprising a window shade, adjustable means engaging an end of the shade to suspend the entire shade, a shade roller on the shade, means to render said shade roller turnable at one time and to keep it from turning other times as the shade is moved, guide elements on the window frame adjacent the longitudinal edges of the shade, means on the free end of the shade to slidably connect the shade to the respective guide elements, and means operatively related to the shade-roller operating means to slidably connect the same to the respective guide elements.

In testimony whereof, I have hereunto set my hand at San Francisco, California, this 3rd day of September, 1929.

THOMAS E. McNULTY.
